THE SPARKS-WITHINGTON COMPANY, A CORPORATION OF OHIO.

MOTOR-HORN.

1,237,717.

Specification of Letters Patent. Patented Aug. 21, 1917.

Application filed May 6, 1913. Serial No. 765,792.

To all whom it may concern:

Be it known that I, WILLIAM SPARKS, of Jackson, in the county of Jackson, in the State of Michigan, have invented new and useful Improvements in Motor-Horns, of which the following, taken in connection with the accompanying drawings, is a full, clear, and exact description.

This invention relates to certain improvements in motor horns adapted to be used as a signal or alarm for automobiles, motor boats and similar machines, and comprises an electric motor attached to one end of a diaphragm case containing a vibratory diaphragm having means thereon coöperating with a motor-driven actuator for vibrating the diaphragm and thereby producing sounds which are amplified by a megaphone attached to the other end of the diaphragm case.

The main object is to increase the electrical efficiency of a two pole motor and, at the same time, to reduce its bulk by reducing the number of parts to such an extent as to allow the entire motor to be applied eccentrically to one end of a diaphragm case wholly within the area of the vibratory part thereof and to allow the use of a central contact or abutment on the diaphragm for co-operative engagement by the motor-driven actuator.

In other words, I have sought to produce a simple, light and powerful motor horn at a considerably lower cost of manufacture than has heretofore been practised without sacrificing any of the advantages of this class of horns.

Another object is to facilitate the adjustment of the diaphragm actuator for wear and volume of tone without displacing any of the parts of the motor or sound-producing device.

Other objects and uses will be brought out in the following description.

45 In the drawings—

Figure 1 is a side elevation of a motor horn embodying the various features of my invention.

Fig. 2 is an end view of the same.

50 Fig. 3 is an enlarged longitudinal sectional view axially through the motor and

sound-producing device, together with the adjacent end of the amplifier taken on line 3—3, Fig. 1.

Figs. 4 and 5 are transverse sectional views taken respectively on lines 4—4 and 5—5, Fig. 1.

Fig. 6 is a detail view of the diaphragm actuator, a portion of a diaphragm and one side of the case being shown in section.

Fig. 7 is a perspective view of one of the brush holders, and Fig. 8 is a similar perspective view of one of the brushes.

Heretofore, so far as I am aware, the field magnets for motor horns of this character have consisted of a cylindrical shell coaxial with the axis of the diaphragm and, therefore, excessively heavy and subject to greater or less dissipation of electric energy which proportionately weakened the efficiency of the motor, but I have discovered that by constructing the motor in a manner herein-after described, it may be materially reduced in size and its power efficiency greatly increased.

In order to accomplish these results, I have provided a two pole electric motor with a field magnet —1— consisting of a U-shape steel frame —2— and cast iron pole pieces —3— which are firmly secured to the inner faces of the opposite arms of the frame —2— by screws —4— having their heads countersunk in the outer faces of said arms as shown more clearly in Figs. 3 and 5.

The frame —2— is preferably made of a single piece or strip of rolled or pressed steel having diametrically opposite, substantially parallel arms spaced apart a sufficient distance to receive between the pole pieces an armature —5—, said arms being united at one end by a diametrically extending cross bar —6— while their opposite ends are bent toward each other in radial lines to form supporting feet —7— parallel with and a sufficient distance apart from the cross bar —6— to receive the revolving parts of the motor.

The entire frame —2— is, therefore, of uniform thickness and preferably of uniform width from end to end, the width being usually the same as the pole pieces —3— which are secured to the opposite arms, said

arms being arcuate in cross section and concentric with the axis of the armature.

The cross bar —6— of the frame —2— is provided with a central aperture —8— and 5 diametrically opposite arms —9— stamped inwardly therefrom parallel with the axis of the motor for receiving diametrically opposite brush holders —10— carrying brushes —11— which contact with the adjacent sides 10 of a commutator —12—, said commutator and also the armature being secured to a motor shaft —13—.

A bushing —14— is secured in the aperture —8— in the cross bar —6— and serves 15 to receive one end of the shaft —13— and also an end-thrust bearing —15— which is adjusted by means of a screw —16— in the outer end of the bushing and coaxial with the shaft for adjusting said shaft endwise 20 to compensate for wear or to vary the volume of tone of the sound-producing device presently described.

The supporting arms —9— for the brush holders —10— are integral with the cross 25 bar —6— and are pressed inwardly beyond the plane of said cross bar to form openings —9'— through which the lead wires, as —a—, of the motor are extended and thence outwardly through an opening in an inclosing 30 shell —17— which surrounds the motor to exclude dust and other foreign matter therefrom and also to prevent malicious or accidental interference with the operation of the motor.

35 The opposite end of the shaft —13— is journaled in a suitable bushing —18— centrally in one of the case sections, as —19—, of the diaphragm case and is provided with an actuator —20— having a circular series 40 of face teeth operating successively against an abutment —21— which is centrally secured to a circular diaphragm —22—, the latter having its marginal edge rigidly clamped between the marginal edge of the 45 case section —19— and an opposed case section —23— forming the base of an amplifier —24—.

The feet —7— of the opposite arms of the 50 motor frame —2— are secured by suitable fastening means, as screws —25—, to the adjacent face of the section —19— of the diaphragm case, said section being provided with an annular reinforcing rib —26— which also serves as a registering stop for 55 alining the motor frame coaxial with its shaft in assembling said frame upon the adjacent end of the diaphragm case.

The actuator —20— preferably consists 60 of a disk tightly secured upon the adjacent end of the shaft between the case section —19— and diaphragm so that by unscrewing the disk and removing the screws —25—, the entire motor may be removed, the case section —23— being also screwed upon the 65 periphery of the section —19—, thus permit-

ting the diaphragm to be removed when necessary or to gain access to the actuator or screws —25—.

Surrounding the pole pieces —3— are suitable field windings —3'— which are 70 electrically connected in the usual manner to the brush holders.

These brush holders are secured in suitable insulating bushings —27— in the apertured arms —9— and are provided with 75 lengthwise sockets open at their inner ends for receiving the brushes —11—, the latter being spring-pressed by springs —28— against the periphery of the commutator —12—.

It will be observed upon reference more particularly to Figs. 4 and 5 that the entire motor is secured to one end of the diaphragm case eccentrically to the axis of said diaphragm a distance corresponding to the 85 radius of the actuator —20— which allows the use of a contact member —21— on the center of the diaphragm, thereby producing a maximum and uniform degree of vibration of such diaphragm and affording deeper 90 and more uniform tones than is possible when the contact member is offset to one side of the center.

The housing —17— for the motor is cylindrical and has its open end tightly fitted 95 upon a circular boss concentric with the axis of the diaphragm but eccentric to the axis of the motor as shown more clearly in Figs. 4 and 5 and its outer end is closed and provided with a removable cap —30— 100 pivoted at —31— to swing transversely of the axis, but is held in its normal position by a catch —32—, said cap being apertured to permit the passage of the wire leads —a— therethrough and when moved from its normal position permits access to the adjusting screw —16— without disturbing any of the other parts of the motor or sound-producing device other than to adjust the actuator into proper coaction with its contact member 110 —21—.

The armature of the motor is yieldingly held against excessive endthrust toward the diaphragm with its opposite end in contact with the ball bearing, by means of a spring 115 —40— extending diametrically across and around the armature shaft and having its ends bearing against the case section —19— and its central portion spring-tensioned against a bushing on said shaft, which bushing engages the adjacent end of the armature core, as shown more clearly in Fig. 3.

It will be observed that the actuator for the diaphragm is also made of pressed sheet metal for economical reasons and also to 125 afford a smoother and harder contact surface for the hardened contact member on the diaphragm than would be possible if made of cast metal.

I have previously stated that one of the 130

objects of the invention is to increase the electrical efficiency of the motor by making the field magnet in the form of a U-shape bar of cold rolled steel, while the pole pieces 5 are preferably made of cast iron, but may be made of bar steel or other suitable magnetizable metal separate from but rigidly secured to the opposite arms of the U-shape bar so as to complete the field magnet of the 10 motor, the outer ends or faces of the pole pieces being concentric with the axis of the motor shaft so as to form and fit snugly against the correspondingly curved sides of the U-shape bar and thereby establish close 15 electrical connection therewith when the pole-pieces are secured thereto by the screws

—4—

By constructing the motor frame in the manner just described including the pole pieces, it is evident that the entire motor 20 may be placed in a comparatively small compact space at one side of the center of the diaphragm or axis of the case —17— a distance corresponding to the radius of the 25 toothed wheel for the purpose previously stated.

Another reason for this increased efficiency is believed to lie in the fact that the magnetic bar is of approximately the same width 30 as the pole pieces and that this relative size reduces dissipation of energy to a minimum, because in the use of cylindrical shells with the same armature and field winding there appears to be a dissipation of energy resulting 35 from the large area over which the magnetic current is distributed.

The main feature of this invention, therefore, resides in the use of a U-shaped magnetic bar, embracing the armature with the 40 feet of its opposite arms secured to one end of a diaphragm case and its opposite end

constituting a support for one end of the motor shaft, the latter having its opposite end journaled in the inner end of the diaphragm case and provided with an actuator 45 and coöoperating with a projection on the center of the diaphragm for imparting vibratory movement thereto.

In addition to these features, the invention also consists in making the U-shaped 50 magnetic bar of substantially the same width as the pole pieces and in securing said pole pieces to the opposite arms of the U-shaped bar intermediate their ends, and in certain other minor features which will be brought 55 out in the claim.

What I claim is:

A horn comprising front and rear case sections for a diaphragm, a diaphragm having its periphery secured between said case 60 sections and its intermediate portion free to vibrate, a wear-piece on the central portion of the diaphragm, a narrow thin sheet metal strip bent in U-shape form and having its ends secured to the rear case section to form 65 a U-shape motor case, pole-pieces rigidly secured to the opposite sides of the motor case and projecting toward each other within the case, brushes carried by and within the case, an armature having its shaft journaled in 70 the rear wall of the U-shape case and in the rear case section, a commutator on the shaft within the U-shape case, an actuator mounted on the shaft and adapted for contact with said wear-piece, and a casing inclosing the 75 U-shape case and other motor parts.

In witness whereof I have hereunto set my hand this 23rd day of April, 1913.

WILLIAM SPARKS.
